ABSTRACT OF THE DISCLOSURE

The response curve of an amplifying device having three electrodes with two resistors connected to two different electrodes thereof is made variable by either a series resonant circuit including a variable resistor adapted to be switched in shunt with one of the aforementioned resistors or by means of series circuits each including a resistor and a capacitor adapted to be switched in shunt selectively or together with the aforementioned resistors.

This invention relates to networks for selectively amplifying certain frequencies more so than other frequencies, i.e., to presence control networks.

It is often desirable to provide monaural or stereophonic sets with a presence control. Such a control may be operated by the listener to permit the listener to hear certain frequencies, say voice frequencies, amplified to a greater extent than other frequencies, say those produced by the instruments of an orchestra accompanying a vocalist.

In accordance with this invention there are provided presence control networks which achieve the foregoing result but which are relatively simple and inexpensive.

In preferred embodiments of this invention, it is possible for the listener to select different frequencies for increased amplification, in contrast to many prior art presence control networks wherein only one band of frequencies that is determined by the manufacturer can be amplified more so than others.

A presence control network embodying this invention includes an amplifying device, which may be either a transistor or an electron discharge device. Assuming the amplifying device to be a transistor, resistors are connected in the emitter and collector circuits thereof, while input signals to be amplified are applied to the base electrode thereof. To a first approximation the gain of such a stage is given by Z_1/Z_2 , where Z_1 is the impedance in the collector circuit and Z_2 is the impedance in the emitter circuit. In one embodiment of this invention, a series resonant circuit is adapted to be connected in parallel through a switch with the emitter resistor or a part thereof, thereby decreasing the impedance in the emitter circuit at the resonant frequency of the series resonant circuit, thus increasing the gain of the stage at this frequency. Preferably a plurality of series resonant circuits are provided, all being resonant at different frequencies, so that different frequencies may be amplified selectively.

In another embodiment of this invention, switches are provided to connect series circuits, each consisting of a resistor and a capacitor, in parallel with the collector and emitter circuit resistors. By closing one or the other or both switches, one can obtain different amplifier response curves.

This invention will become more apparent from the following detailed description, taken in conjunction with the appended drawings, in which:

FIGURE 1 shows a transistor network embodying this invention;

FIGURE 2 is the same network as shown in FIGURE 1

but with an electron discharge device replacing the transistor;

FIGURES 3 and 4 show another network embodying this invention using a transistor and an electron discharge device respectively; and

FIGURES 5-8 are amplifier response curves (not to scale), FIGURE 5 being the response curve of the circuit of FIGURE 1, and FIGURES 6-8 being three of the different response curves which can be obtained with the circuit of FIGURE 3.

Referring to FIGURE 1, input signals to be amplified are applied to the base electrode of a transistor TR10 via a coupling capacitor C_c . This transistor is biased on via resistors R_a and R_b that are connected in series circuit between two terminals 10 and 11 at different D.C. potentials, namely B_+ and ground respectively, the common terminal of resistors R_a and R_b being connected to the base electrode of transistor TR10.

A resistor R_c is connected between terminal 10 and the collector electrode of transistor TR10, while resistors R_{10} and R_e are connected in series with each other between terminal 11 and the emitter electrode of transistor TR10.

Output signals are derived from a terminal 12 connected to the common terminal of resistor R_c and the collector electrode of transistor TR10 by a blocking or coupling capacitor C_b .

Adapted to be connected in parallel with resistor R_e by means of a switch S10 are a plurality of series resonant circuits each resonant at a different frequency. Common to each series resonant circuit is a variable resistor R_{11} and an inductance coil L_{10} . In the embodiment of the invention shown there are four capacitors C_{10} , C_{11} , C_{12} and C_{13} each having a different capacitance value, so four different series resonant circuits each including a different one of capacitors $C_{10}-C_{13}$ can be selected depending upon the position of switch S10. As shown, one terminal of each of capacitors $C_{10}-C_{13}$ is connected to ground, i.e., to terminal 11, while the other terminals of capacitors $C_{10}-C_{13}$ are connected to switch contacts 13, 14, 15 and 16 respectively. A contact 17 for "switch open" is provided.

Resistor R_{10} performs a current limiting function at resonance and could be located in the series resonant circuit shunting resistor R_e , if desired. Off resonance, resistor R_{10} and resistors R_c and R_e determine the minimum gain.

The network of FIGURE 2 is very similar to the network of FIGURE 1, the basic difference being the substitution of an electron discharge device 20 in the form of a triode for transistor TR10. Otherwise the networks are the same except for the manner of applying bias to the grid electrode of triode 20. To differentiate plate resistor R_L from collector resistor R_c and cathode resistor R_{12} from emitter resistor R_e , different symbols have been used, otherwise the same symbols have been used in FIGURES 1 and 2 to designate the same components, as is the case in respect of FIGURES 1 and 3 and FIGURES 2 and 4.

The network of FIGURE 3 differs from the network of FIGURE 1 in that switch S10 has been omitted as well as all series resonant circuits. In place thereof there is provided a series circuit consisting of a resistor R_{13} and a capacitor C_{14} which is adapted to be connected in parallel with resistor R_c when a switch S2 is closed, and a series circuit consisting of a resistor R_{14} and a capacitor C_{15} which is adapted to be connected in parallel with resistor R_e when a switch S3 is closed.

The network of FIGURE 4 differs from that of FIGURE 2 in the same way that the networks of FIGURES 1 and 3 differ from each other.

The operation of the network shown in FIGURE 1 now will be discussed. When switch S10 is on contact 17,

there is no series resonant circuit shunting resistor R_e . Under these circumstances, provided that $h_{21}(R_e + R_{10}) \gg h_{11}$, the gain of the stage is approximately equal to the ratio of Z_1 to Z_2 . This also is true with switch $S10$ on any contacts **13**, **14**, **15** or **16**. In this latter case

$$Z_1 = R_e \quad (1)$$

and

$$Z_2 = R_{10} + \frac{R_e \left(R_{11} + j\omega L_{10} - \frac{j}{\omega_c} \right)}{R_e + R_{11} + jL_{10} - \frac{j}{\omega_c}} \quad (2)$$

C=C10, C11, C12 or C13

R_{11} includes the resistance of coil **L10**

At resonance

$$Z_2 = R_{10} + \frac{R_e R_{11}}{R_e + R_{11}} \quad (3)$$

Well off resonance

$$Z_2 \approx R_{10} + R_e \quad (4)$$

Thus, as may be seen by reference to Equations 1 and 4, and the fact that

$$\text{Gain} \approx Z_1 / Z_2 \quad (5)$$

at frequencies well off resonance, the response curve of the amplifier will be flat and is given by the formula

$$\text{Gain} \approx \frac{R_e}{R_{10} + R_e} \quad (6)$$

At these frequencies the response is indicated by portions 20 of curve A of FIGURE 5.

However, when it is desired to amplify a certain frequency f_0 more so than other frequencies, switch $S10$ may be moved to the position shown in FIGURE 1 where it engages contact **13**, thus placing a series resonant circuit consisting of resistor R_{11} , inductance coil **L10** and capacitor **C10** in parallel with resistor R_e . This series resonant circuit is resonant at frequency f_0 and has a low impedance at its resonant frequency. Under these conditions, the gain of the amplifier at resonance is given by the following equation:

$$\text{Gain} \approx \frac{R_e}{R_{10} + \frac{R_e R_{11}}{R_e + R_{11}}} \quad (7)$$

Equation 7 determines the response at f_0 , i.e., the gain at point **21** of curve A of FIGURE 5. By varying resistor R_{11} , one can vary the gain f_0 , i.e., the vertical position of point **21**. If resistor R_{11} is set to zero, resistor R_{10} then controls the maximum increase in gain that can be achieved at the desired frequency f_0 . The effect of the series resonant circuit being placed in parallel with resistor R_e is, as aforementioned, to decrease Z_2 , thereby increasing the gain of the amplifier at series resonant frequency f_0 . Bandwidth is controlled by the choice of **L10**, **C10-C13**, R_e , R_{10} and R_{11} .

By moving switch $S10$ to contact different contacts **14**, **15** and **16**, the peak in the response curve of the amplifier can be made to occur at different frequencies f_{01} , f_{02} , f_{03} corresponding to the resonant frequencies of the three different series resonant circuits that are completed when switch $S10$ engages contacts **14**, **15** and **16** respectively. In this way voice frequencies or different musical instruments may be emphasized.

The operation of the network shown in FIGURE 2 will be immediately apparent from the operation of the network of FIGURE 1 as described above.

The operation of the network of FIGURE 3 now will be described.

When both switches **S2** and **S3** are open, provided that $h_{21}R_e \gg h_{11}$,

$$\text{Gain} \approx \frac{Z_1}{Z_2} = \frac{R_e}{R_e} \quad (8)$$

(Z_1 is the impedance of the collector circuit. Z_2 is the impedance of the emitter circuit). In other words, the amplifier will have a flat response curve over a particular frequency range.

When switch **S2** is closed but switch **S3** is kept open, the series circuit consisting of resistor **R13** and capacitor **C14** is connected in parallel with resistor R_e . Because of the fact that the impedance of capacitor **C14** decreases with increasing frequency, and because the gain of the stage to a first approximation given by the ratio of Z_1 to Z_2 , the response curve of the amplifier will be as shown in FIGURE 6, the response being higher at lower frequencies than at higher frequencies. This may be seen more clearly from the fact that at low frequencies when the impedance of capacitor **C14** is high

$$\text{Gain} \approx R_e / R_e \quad (9)$$

At higher frequencies, however the gain falls off to

$$\frac{R_e R_{13}}{R_e + R_{13}} \quad (10)$$

the general gain equation being as follows:

$$\text{Gain} = \frac{R_e \sqrt{R_{13}^2 \omega^2 C_{14}^2 + 1}}{\sqrt{(R_e + R_{13})^2 \omega^2 C_{14}^2 + 1}} \quad (11)$$

The response curve of the amplifier with switch **S2** closed and switch **S3** open is shown in FIGURE 6, as aforementioned. The frequency f_3 where the gain is 3 db below the maximum gain and the frequency f_4 where the gain is 3 db above the gain given by Formula 10 may be calculated readily in terms of the size of capacitor **C14** required. The manner of calculation will become apparent after consideration of the operation of the circuit with switch **S2** open and switch **S3** closed.

When switch **S3** is closed but switch **S2** kept open, a series circuit consisting of resistor **R14** and capacitor **C15** is connected in parallel with resistor R_e . With switch **S3** closed and switch **S2** open, the response curve of the amplifier will be shown in FIGURE 7, this being on account of the decreasing impedance of capacitor **C15** with increasing frequency, and the fact that the gain of the stage is approximately given by the ratio of Z_1 to Z_2 . Under these circumstances, the amplifier has a higher gain for higher frequencies than it does for lower frequencies. This may be seen from the fact that at low frequencies when the impedance of capacitor **C15** is high,

$$\text{Gain} \approx R_e / R_e \quad (12)$$

At higher frequencies, however, the gain rises to

$$\frac{R_e}{\frac{R_e R_{14}}{R_e + R_{14}}} \quad (13)$$

the general gain equation being as follows:

$$\text{Gain} = \frac{R_e}{\frac{R_e \sqrt{R_{14}^2 \omega^2 C_{15}^2 + 1}}{\sqrt{(R_e + R_{14})^2 \omega^2 C_{15}^2 + 1}}} \quad (14)$$

The frequency f_2 at which the gain is down 3 db from the maximum gain may be determined by equating the ratio of (13) and (14) to $\sqrt{2}$ and solving for ωC_{15} . Since ω is set by design requirements, the value of capacitor **C15** can be found in terms of the required frequency f_2 where the gain is down 3 db from maximum. Once the value of capacitor **C15** is established, the frequency f_1 at which the gain is 3 db above the minimum given by Equation 12 can be determined.

Obviously the initial gain and the increase in gain are determined by the values of R_e , R_{14} and R_{15} .

With both switches S2 and S3 closed, and with

$$\frac{R_e}{R_e} = \frac{R_{13}}{R_{14}}$$

the latter condition resulting from the requirement that at the upper and lower frequency limits the gain must be the same, the response curve of the amplifier will be as shown in FIGURE 8.

At low and high frequencies the gain is approximately R_c/R_e . At frequencies between f_2 and f_3 , assuming f_3 is chosen to be greater than f_2 , and after a level response has been obtained, the gain reaches a maximum of approximately

$$\frac{R_e}{\frac{R_e R_{14}}{R_e + R_{14}}}$$

The gain increase from R_c/R_e to its maximum is due to a decrease in emitter circuit impedance. After the maximum gain is reached, emitter circuit impedance changes cease to be significant and the decrease in gain to the original gain of R_c/R_e is attributable to decreasing collector circuit impedance.

It will be seen that depending upon the position of switches S2 and S3, four different amplifier response curves can be obtained.

The operation of the network of FIGURE 4 will be immediately apparent from the description of the operation of the network of FIGURE 3.

In respect of the networks of FIGURES 2 and 4, with the various switches open it should be understood that

$$\text{Gain} \approx \frac{R_L}{R_{10} + R_{12}} \quad (\text{FIG. 2})$$

or

$$R_L/R_{12} \quad (\text{FIG. 4})$$

if

$$(\mu + 1)(R_{10} + R_{12}) \gg rp + R_L \quad (\text{FIG. 2})$$

or

$$(\mu + 1)R_{12} \gg rp + R_L \quad (\text{FIG. 4})$$

If these conditions do not hold, the effect of μ and rp must be included in the overall design.

While preferred embodiments of this invention have been disclosed, those skilled in the art will appreciate that changes and modifications may be made therein without departing from the spirit and scope of this invention as defined in the appended claims.

I claim:

1. A network for selectively amplifying certain frequencies more than other frequencies comprising: an amplifying device having first, second and third electrodes; means for applying an input signal to be amplified by said amplifying device to said first electrode; a first resistor connected in series circuit between said second electrode and a first terminal at a first D.C. potential; a second resistor connected in series circuit between said third electrode and a second terminal at a second D.C. potential different from said first D.C. potential; means connected to said second electrode for deriving an output signal from said network; a switch; and a series resonant circuit adapted to be connected in parallel with said second resistor when said switch is closed and comprising a variable resistor, an inductance coil and a capacitor.

2. A network according to claim 1, wherein said amplifying device is a transistor having base, collector and

emitter electrodes, said first electrode being said base electrode, said second electrode being said collector electrode, said third electrode being said emitter electrode.

3. A network according to claim 1, wherein said amplifying device is an electron discharge device having plate, cathode and grid electrodes, said first electrode being said grid electrode, said second electrode being said plate electrode, said third electrode being said cathode electrode.

4. A network according to claim 1, wherein there are a plurality of said capacitors, said capacitors having different capacitance values, said switch being operable to select different ones of said capacitors for inclusion in said series resonant circuit, whereby series resonant circuits resonant at different frequencies may be connected in parallel with said second resistor.

5. A network for selectively amplifying certain frequencies more than other frequencies comprising: an amplifying device having first, second and third electrodes; means for applying an input signal to be amplified by said amplifying device to said first electrode; a first resistor connected in series circuit between said second electrode and a first terminal at a first D.C. potential; a second resistor connected in series circuit between said third electrode and a second terminal at a second D.C. potential different from said first D.C. potential; means connected to said second electrode for deriving an output signal from said network; a first switch; a first series circuit adapted to be connected in parallel with said first resistor when said first switch is closed and comprising a third resistor and a first capacitor; a second switch; and a second series circuit adapted to be connected in parallel with said second resistor when said second switch is closed and comprising a fourth resistor and a second capacitor.

6. A network according to claim 5, wherein said amplifying device is a transistor having base, collector and emitter electrodes, said first electrode being said base electrode, said second electrode being said collector electrode, said third electrode being said emitter electrode.

7. A network according to claim 5, wherein said amplifying device is an electron discharge device having plate, cathode and grid electrodes, said first electrode being said grid electrode, said second electrode being said plate electrode, said third electrode being said cathode electrode.

8. A network according to claim 6, wherein the ratio of the resistance of said first resistor to the resistance of said second resistor is equal to the ratio of the resistance of said third resistor to the resistance of said fourth resistor.
